UNITED STATES PATENT OFFICE.

GEORGE F. WELLS, OF SAN FRANCISCO, AND RAYMOND R. MORGAN, OF BEVERLY HILLS, CALIFORNIA.

DESIGN FOR A COMBINATION COIN RECEPΤΑCLE AND CARD HOLDER.

Application filed January 25, 1928. Serial No. 25,033. Term of patent 3½ years.

To all whom it may concern:

Be it known that we, GEORGE F. WELLS and RAYMOND R. MORGAN, citizens of the United States, and residents, respectively, of the city and county of San Francisco, State of California, and the city of Beverly Hills, State of California, have invented a new, original, and ornamental Design for a Combination Coin Receptacle and Card Holder, of which the following is a specification, reference being had to the accompanying drawings, forming part thereof.

Figure 1 is a front view of the article, showing my new design; and
Fig. 2 is a side view thereof.

We claim:

The ornamental design for a combination coin receptacle and card holder substantially as shown.

GEORGE F. WELLS.
RAYMOND R. MORGAN.
